UNITED STATES PATENT OFFICE.

CHARLES EDWARD HAVILAND, OF LIMOGES, FRANCE.

DESIGN FOR A DISH.

SPECIFICATION forming part of Design No. 25,513, dated May 19, 1896.

Application filed April 15, 1896. Serial No. 587,730. Term of patent 7 years.

To all whom it may concern:

Be it known that I, CHARLES EDWARD HAVILAND, a citizen of the United States, residing at the city of Limoges, in the Republic of France, have invented and produced a new and original Design for a Dish or Bowl, of which the following is a specification, reference being had to the accompanying drawings, forming part thereof, and in which—

10 Figure 1 is a side elevation of a dish or bowl bearing and incorporating my design, and Fig. 2 is a sectional view of a portion of same on the dotted line 2 2 of Fig. 1.

15 The leading features of my design consist in the ornamental form and configuration of the dish or bowl substantially as shown in the accompanying drawings.

The sides of the dish or bowl are composed of the scalloped sections A, which curve downward and inward to the scalloped base B. 20 The upper edges of the sides of the dish or bowl bear the ornamental band C, at whose lower edge is the scalloped scroll ornamentation D. The sides of the base B bear the scroll ornamentation E. 25

What I claim is—

The design for a dish or bowl, substantially as shown and described.

Signed at Limoges, in the Republic of France, this 2d day of April, 1896.

CHARLES EDWARD HAVILAND.
